FRY PAN

Dominic J. De Fano, River Grove, Ill., assignor to McGraw-Edison Company, Milwaukee, Wis., a corporation of Delaware

Continuation of design applications Ser. No. 75,994, July 26, 1963, and Ser. No. 76,212, Aug. 14, 1963. This application Apr. 28, 1964, Ser. No. 79,855

Term of patent 14 years

(Cl. D44—1)

FIG. 3.

FIG. 4.

FIG.5.

FIG.6.

FIG. 7.

FIG. 8.

FIG. 1 is a perspective view of a fry pan, showing my new design, wherein the pan is substantially square in form and the pan and cover are of substantially the same height;

FIG. 2 is a plan view thereof;

FIG. 3 is a side elevational view thereof;

FIG. 4 is a sectional view taken along line 4-4 of FIG. 2;

FIG. 5 is a perspective view of another embodiment of a fry pan showing my new design, wherein the pan is substantially rectangular in form, being wider than it is deep, and the cover is substantially twice the height of the pan;

FIG. 6 is a plan view of the embodiment of FIG. 5;

FIG. 7 is a side elevational view of the embodiment of FIG. 5; and

FIG. 8 is a sectional view taken along line 8-8 of FIG. 6.

The dominant features of my design are shown in the full line portions of the drawings.

This application is a continuation of my earlier filed applications, Serial No. D. 75,994, of July 26, 1963, and

Serial No. D. 76,212 of August 14, 1963, both now abandoned.

I claim:

The ornamental design for a fry pan, as shown and described.
